(57) **CLAIM**

An ornamental design for a towable water sports equipment,
as shown and described herein.

DESCRIPTION

FIG. 1 is a front perspective view as taken from the upper
front of a towable water sports equipment of the present
invention showing my new design;

FIG. 2 is a top plan view thereof;

FIG. 3 is an upper left side perspective view, offset to the
rear, the upper right side perspective view, offset to the rear,
being a mirror image thereof;

FIG. 4 is an upper right side perspective view, offset to the
rear, the upper left side perspective view, offset to the rear,
being a mirror image thereof;

FIG. 5 is a front perspective view as taken from an upper
left; and,

FIG. 6 is a bottom perspective view thereof.
